JOURNAL BOX

Donald S. Barrows, Rochester, N. Y., assignor to
 The Symington-Gould Corporation, Depew,
 N. Y., a corporation of Maryland

Application February 27, 1947, Serial No. 731,221

25 Claims. (Cl. 308—38)

1

This invention pertains to a journal box for use in a railway truck.

An object of the invention is the provision of an improved journal box arranged to carry at a side thereof a snubber or friction creating means.

Another object of the invention is the provision of an improved journal box having at a side thereof means for supporting a yieldable means and means for supporting or carrying a snubber.

A further object of the invention is the provision, in a journal box, of a housing facing outwardly of the journal box for the accommodation of a snubber.

These and other objects of the invention will become apparent from the succeeding description which is to be considered together with the accompanying drawing wherein:

Figure 1 is a partial plan view and a partial horizontal sectional view of a journal box embodying the present invention.

Figure 2 is a partial front elevational view and a partial vertical sectional view of the journal box shown in Figure 1.

Figure 3 is a side elevational view of the journal box shown in Figures 1 and 2.

Referring now in detail to the drawing, wherein like reference characters indicate like parts, the numeral 1 is employed to designate, in a somewhat general manner, a journal box exemplary of the present invention. This structure, to be described in detail hereinafter, is related to the journal box illustrated and described in my copending application Serial Number 630,230, filed November 23, 1945 and the copending application of Glenn F. Couch, Serial Number 668,129, filed May 8, 1946. The present invention is particularly adapted to be incorporated in a journal box which is capable of appreciable and predetermined movements transversely of a railway truck of which it forms a part. Only a fragment of a side frame part 2 of the railway truck is illustrated in the drawing and that part only by diagrammatic lines because of the reference to the above named co-pending applications and also because the side frame forms no part of the present invention. As will be brought out more in detail hereinafter the side frame and journal box are also arranged for relative vertical movements.

Considering the construction of the journal box in detail it will be noted by referring to the several views of the drawing that it may and preferably is made, in the main, as a casting and comprises a top wall or roof 3 disposed hori-

2

zontally. From the lateral edges of the roof there depend transversely spaced, vertical sides or side walls 4 which, at their lower edges, curve inwardly of the journal box to form the usual well or bottom wall 5. The forward or leading edges of all the walls define an aperture 6 which permits access to the interior of the journal box and which is covered by a movable lid (not shown). The side walls are provided with front and rear guide lugs 7 spaced an appreciable distance apart to permit a transverse movement of the journal box and also to confine such movement to a predetermined or limited distance. The guide lugs extend outwardly of or away from the interior of the box in a direction longitudinally of the truck and they also extend in a vertical direction so as to come into surface bearing relation with a companion side frame upon the box reaching the limits of its transverse movements.

Directed horizontally at or about the juncture of the side and bottom walls are oppositely extended brackets, wings or shelves 8 which form seats for yieldable means or springs 9, the latter of which function as direct and flexible supports for the side frame.

In order to reinforce the shelves against stresses to which they will be subjected in service, depending ribs or flanges 10 are formed integrally with the bottom wall to underlie and form a part of the brackets. While various means may be employed to function as spring positioning means it is preferred, at the present writing, to form on or at the outer corners of each shelf a plurality of somewhat triangular posts or studs 11 arranged in transverse spaced relation in an upstanding fashion. Thus the studs, while spaced a slight distance from a related spring, do form obstructions and prevent the spring from shifting transversely of the truck and away from the journal box off of its supporting shelf.

It is also important, for reasons to be made hereinafter apparent, that each spring be restricted from shifting toward the journal box from its illustrated position and accordingly each shelf is provided with integrally formed, circular or partial or transversely spaced collars 12 arranged in the close proximity to a related spring. The collars upstanding from the shelves are preferably of a height equal to the studs and together with the latter, maintain the springs in fixed predetermined positions. It may be well to add here that the springs are disposed in a longitudinal vertical plane passing through a vertical axis of the side frame and this plane

will be hereinafter referred to as a vertical axis

of the journal box. The vertical axis of the journal box is characterized in the drawing in Figure 1 only, by the diagrammatic line A—A.

So as to snub, retard or check not only harmonic actions of the side frame supporting springs but also transverse movements of the journal box, there is associated with preferably each side of the journal box a friction creating means 13 commonly termed a friction or snubber means. Since the friction shoes 14 and interposed spreading or spring means of the friction means forms no part of the present invention they are, however, shown by diagrammatic lines so as to illustrate their association with related structure. However, for a complete understanding of the function of the parts herein shown by diagrammatic lines reference is hereby made to the above mentioned copending applications. The friction creating shoes are by the instant structure carried by the journal box. The shoes 14 and the journal box are arranged for relative transverse movements while the shoes and side frame are arranged for relative vertical movements and thus all relative journal box and side frame movements are controlled.

Toward the accomplishment of carrying the friction shoes and interposed spring there is provided on each journal box side wall, a bottom ledge or abutment 15 in or adjacent to a horizontal plane passing through the axis of an axle 16 the latter of which is indicated diagrammatically and the former or horizontal plane is indicated by the lines B—B. The bottom ledge of each side wall is positioned midway between the guide lugs and accordingly the longitudinal center of each bottom shelf coincides with the vertical axis of the journal box. Further each bottom ledge is positioned intermediate the height of a related side wall in upper spaced relation to an associated wing but since the snubbing means must clear the side frame supporting springs the bottom ledges are limited in area or of less longitudinal or horizontal extent than the shelves. Because the journal box is arranged to move horizontally or transversely relative to the shoes each bottom ledge is provided with a liner plate 17 which is secured to the ledge by means of welds 18 or any other selected means.

In order to overcome any service hinging tendency or action of each bottom abutment or ledge, there is provided a pair of transversely spaced ribs or flanges 19 in supporting relation to a ledge and formed integrally with the associated side wall. Each set of ribs depend vertically from a ledge to a subjacent bracket where they are turned horizontally or longitudinally of the truck to merge with extremities of companion partial collars.

Each journal box side wall adjacent a top thereof is formed with a brass lug 20 whereby the side wall proper is convoluted or turned inwardly of the journal box to present an obstruction against which a journal brass (not shown) may bear in service. The brass lug is formed adjacent to the upper limits of each side wall above the horizontal plane B—B and thus presents an outwardly facing housing or indentation 21.

In order to facilitate the manufacture of the journal box, an upper ledge 22 of each side wall is formed or made separately from the journal box. The top ledges cooperate with the bottom ledges to hold the shoes substantially stationary with the journal box, as a side frame moves, due to the yielding actions of the coil springs, in

a vertical direction. While the top ledges may be formed as an integral cast part of the journal box as clearly taught by the copending applications above referred to, it is, however, preferred at the present writing to make the top ledge as a forging or if desired a separate casting and by this manner of manufacture the top ledge may be properly gauged from the bottom ledge as the former is attached to each side wall. Each top ledge is made as an angle-shaped bracket with a vertically disposed leg or arm 23 fitting into the indentation presented by the brass lug to be thus positioned in back of an outwardly directed or working face 24 of a related side wall. By thus disposing the vertical bracket leg in an indentation, the usual or conventional brass lug cavity may be conveniently utilized and the vertical leg will be thus removed from the working face 24 of the side wall. In furtherance of what has been said previously, each vertical leg terminates adjacent to its upper extremity in a horizontally disposed leg or top ledge 25 which like its counterpart, the lower ledge, extends away from a related side wall longitudinally of the truck. Each top leg or ledge is positioned directly over a companion lower ledge and thus it also is arranged to extend beyond each side of the vertical axis A—A of the journal box by an amount so as not to interfere with the side frame during relative transverse movement between the journal box and side frame. After each top leg or ledge is gauged the proper and exact distance from a companion lower ledge, the bracket is secured to each side wall by any desired means such as the illustrated welds 26. Each bracket top ledge is provided with an underlying liner plate 27 which is attached to the top ledge preferably by welds 28. Thus the liner plates 17 and 27 are arranged to contact the shoes and relieve the top and bottom ledges of any abrasive actions of the shoes as such actions may from time to time occur. Since the side walls will also be subjected to abrasive actions of the shoes unless some safeguarding means are not present, it is at the present writing deemed advisable to provide each side wall with a liner 29. Each such liner bears against an outwardly facing surface 24 of a related side wall and extends transversely of the truck to the proximity of the guide lugs while it extends vertically to the proximity of the top and bottom ledge (see Figure 3 particularly). Any fastening means such as welds 30 may be employed to retain the liners 29 in illustrated and operable position. As will be noted by referring particularly to Figure 2 of the drawing the bracket vertical leg is disposed in back of each liner 29 and thus the liner presents a smooth, true and unobstructed exposed face 31 against which the shoes may bear or brush as occasioned by service movements.

From the above it will be noted that various changes and alterations may be made to the illustrated and described specie of this invention without departing from the spirit of this invention or the scope of the appended claims.

I claim:

1. In a journal box having brass lugs, the combination of, vertically spaced means outstanding from sides of said journal box for accommodation of friction means, some of said vertically spaced means outstanding from said brass lugs only of said journal box and bearing surfaces facing one another vertically and fixed relative to said vertically spaced means.

2. In a journal box having brass lugs, the combination of, vertically spaced horizontally directed means outstanding from side walls of said journal box for the accommodation of friction means, some of said vertically spaced horizontally directed means being formed separately from said journal box and secured thereto within said brass lugs only thereof.

3. In a journal box, the combination of, vertically spaced ledges outstanding from a side wall of said journal box for the accommodation of friction means, and a spring supporting shelf below said ledges.

4. In a journal box, the combination of, vertically spaced ledges outstanding from a side wall of said journal box for the accommodation of friction means, and a spring supporting shelf of greater extent than said ledges disposed horizontally below said ledges.

5. In a journal box, the combination of, vertically spaced ledges outstanding from a side wall of said journal box for the accommodation of friction means, a shelf of greater horizontal extent than and positioned below said ledges for supporting a spring, and means on said shelf for maintaining a spring in operable position.

6. In a journal box, the combination of, vertically spaced horizontal ledges outstanding from a side wall of said journal box for the accommodation of friction means, and a horizontal shelf extending beyond the limits of said ledges from said journal box; said shelf being arranged to support a spring, one of said ledges being formed separately and secured to said journal box.

7. In a journal box, the combination of, vertically spaced ledges outstanding from a side wall of said journal box, one of said ledges being formed separately and secured to a side wall of said journal box; said vertically spaced ledges having horizontal bearing surfaces facing one another vertically.

8. In a journal box having a brass lug forming an indentation in a side wall thereof, the combination of, a spring seat formed on said side wall, a ledge formed on said side wall in vertical spaced relation to said spring seat, and a second ledge in vertical spaced relation to said first named ledge and extending out of said brass lug forming indentation.

9. In a journal box having a brass lug forming an indentation in a side wall thereof, the combination of, a spring seat formed on said side wall adjacent a lower extremity of said side wall, a ledge outstanding from said side wall intermediate the height thereof, and another ledge spaced above said first named ledge and having a portion thereof disposed within said indentation.

10. In a journal box, the combination of, vertically spaced ledges outstanding from a side wall of said journal box for the accommodation of friction means, a spring supporting shelf below said ledges, and spring positioning means on said shelf.

11. In a journal box, the combination of, vertically spaced ledges outstanding from a side wall of said journal box for the accommodation of friction means, a spring supporting shelf below said ledges, and ribs extending between said shelf and one of said ledges.

12. In a journal box, the combination of, vertically spaced ledges outstanding horizontally from a side wall of said journal box for the accommodation of friction means, one of said ledges being formed integrally with said side wall

and the other of said ledges being welded to said side wall.

13. In a journal box, the combination of, vertically spaced ledges outstanding horizontally from a side wall of said journal box for the accommodation of friction means, one of said ledges being formed integrally with said side wall intermediate the height thereof and another of said ledges being welded to said side wall adjacent an upper edge thereof.

14. In a journal box, the combination of, a horizontal ledge outstanding from a side wall of said journal box intermediate the height thereof, an angle-shaped bracket having one part thereof disposed within a brass lug formed in said side wall adjacent a top thereof, and another part of said bracket extending horizontally in upper spaced relation to said ledge.

15. In a journal box of the type having a side wall and front and rear guide lugs, the combination of, a ledge between and spaced from said guide lugs and positioned intermediate the height of said side wall, means having one part thereof secured to said side wall within an indenture therein, another part of said means directly overlying said ledge in spaced relation thereto, and a plate secured to said side wall between said guide lugs, ledge and last named means part.

16. In a journal box of the type having a side wall and front and rear guide lugs, the combination of, a ledge between and spaced from said guide lugs and positioned intermediate the height of said side wall, means having one part thereof secured to said side wall within an indenture therein, another part of said means directly overlying said ledge in spaced relation thereto, and a plate secured to said side wall between said guide lugs, ledge and last named means part; said plate being positioned in front of said first named means part.

17. In a journal box of the type having a side wall and front and rear guide lugs, the combination of, a ledge between and spaced from said guide lugs and extending substantially horizontally from said side wall, another ledge spaced directly above said first named ledge in spaced and substantially parallel relation thereto; said ledges being arranged to accommodate a friction means, and a plate secured to said side wall between said lugs and ledges.

18. In a journal box, the combination of, vertically spaced ledges outstanding horizontally from a side wall of said journal box for the accommodation of a friction means, a shelf extending from said side wall beyond the limits of said ledges, reinforcing means joining one of said ledges and shelf, and spring positioning means upstanding from said shelf.

19. In a journal box, the combination of, vertically spaced ledges outstanding from a side wall of said journal box for the accommodation of friction means, one of said ledges being positioned intermediate the height of said journal box, and both of said ledges carrying vertically spaced horizontal bearing surfaces facing one another.

20. In a journal box, the combination of, vertically spaced horizontal ledges outstanding from a side wall of said journal box for the accommodation of friction means, and a horizontal shelf extending beyond the limits of said ledges from said journal box; said shelf being arranged to support a spring and being of greater width than said ledges.

21. In a journal box having transversely spaced guide lugs at sides thereof, the combination of, vertically disposed horizontal ledges outstanding from sides of said journal box intermediate and normal to said guide lugs, said ledges outstanding horizontally beyond some of said guide lugs.

22. In a journal box having transversely spaced guide lugs at sides thereof, the combination of, vertically spaced ledges outstanding from sides of said journal box for the accommodation of friction means, some of said ledges being disposed intermediate the height of said journal box, and all of said ledges being interposed between said guide lugs and of greater horizontal extent than some of said guide lugs.

23. In a journal box having transversely spaced guide lugs at sides thereof, the combination of, vertically arranged ledges outstanding from sides of said journal box for the accommodation of friction means and being of less width than the distance between said guide lugs, some of said ledges being near one vertical limit of said journal box, and some of said ledges being between the vertical limits of said journal box.

24. In a journal box having transversely spaced guide lugs at sides thereof, the combination of, vertically arranged ledges outstanding

5 from sides of said journal box for the accommodation of friction means and being of less width than the distance between said guide lugs, some of said ledges being near one vertical limit of said journal box, some of said ledges being between the vertical limits of said journal box; and all of said ledges extending horizontally beyond the limits of some of said guide lugs.

10 25. In a journal box, the combination of, a horizontal ledge member outstanding from a side wall of said journal box, an angle-shaped bracket member having one vertical part thereof secured to said journal box and another part extending horizontally in vertical spaced relation to said ledge member, and one of said members being disposed intermediate the height of said journal box.

DONALD S. BARROWS.
